FLUID ACTUATED TOOL

John E. Renfer and Alfred G. Slatcher, Cleveland,
Ohio, assignors to The Cleveland Rock Drill
Company, Cleveland, Ohio, a corporation of
Ohio

Application May 13, 1930, Serial No. 452,099

6 Claims. (Cl. 121—7)

This invention relates broadly to fluid operated tools of the percussive type and more specifically to an improved mechanism for effecting the rotation of the cutting tool.

One object of this invention is to provide a self-rotating fluid actuated tool with a mechanism which will facilitate and render safer the operation of the tool.

Another object of this invention is to provide a fluid actuated tool with means for releasing the automatic rotating mechanism and organizing the parts of the tool for hand rotation.

Another object of this invention is to provide a rock drilling machine of the stoper type with a rotation controlling device which can readily be manipulated by the operator when the rotative movement of the cutting tool becomes restrained while drilling rock or other similar material of variable density.

Other objects more or less ancillary to the foregoing and the manner in which all the various objects are realized will appear in the following description which, considered in connection with the accompanying drawings, sets forth the preferred embodiment of the invention.

In the drawings:

Fig. 1 is a vertical sectional view of a pneumatic tool illustrating the various parts of the mechanism positioned for an automatic rotation of the cutting tool.

Fig. 2 is a view similar to Figure 1 illustrating the various parts of the mechanism positioned for hand operated rotation of the cutting tool.

Fig. 3 is a perspective view partly in section of the chuck.

Fig. 4 is an enlarged perspective view of the ratchet ring.

The fluid actuated tool herein chosen for the purpose of illustrating the invention embodies a stoper drill of the hammer type which comprises a cylinder 10 within which is reciprocably mounted a piston 11 having an extended fluted stem portion 12 operatively associated with the cutting tool by way of a chuck 13 such as is ordinarily used in tools of this type. The cylinder body is formed to accommodate the support of a handle 14 which is mounted therein with a tapered socket 15 being secured by two semi-circular members 16 held in place by a screw threaded bushing 17. Adjacent the end of the handle 14, is a vertically disposed casing in which is mounted a valve 18 having a rotatable control knob 19.

Within the cylinder 10, is a valve 20 organized to effect the distribution of the motive fluid, said

valve being mounted for reciprocative movement within a valve block 21 fitted snugly within cylinder 10. The movement of the valve and the consequential reciprocative movement of the piston 11 are effected in a manner common in tools of this type, and since the operation of this portion of the mechanism forms per se no part of the present invention no further description of these elements need be given here further than to direct attention to an orifice or exhaust port 22 in the cylinder 10, which is arranged in relation to the path of movement of the piston 11 to afford communication between the cylinder and the atmosphere during the operation of the tool.

Adjacent the valve block 21 and interposed between bearing plate 23 and head block 24 is a ratchet mechanism 25 comprising a toothed ring 26 provided with a plurality of apertures 27, and a plurality of pawls 28. The pawls are adapted to engage the teeth of the ratchet, and the ring 26 is restrained from rotation by a pin 29 adapted to engage in one of the apertures 27. The pin 29 is formed with an enlarged portion or head 30 slidably mounted within a bore 31 closed by a screw threaded bushing 32. Adjacent the head 30 is a pressure chamber 33 adapted to be connected to the source of motive fluid by way of canals 34 and 35.

The chuck is provided with a plurality of radially disposed recesses 36 adapted to receive 30 a pin 37 which is formed with an enlarged portion or head 38 slidably mounted within a bore 39 terminated by a screw threaded bushing 40. The latter is formed with a pressure chamber 41 adapted to be connected to the source of motive fluid by way of canals 42 and 35. Adjacent the head 38 is a spring 43 restraining the pin 37 from engaging within the recesses 36.

A rifled stem 55 is coordinated with the ratchet ring 26 and is maintained within the head of the piston 11 in a bore of complementary configuration. The ratchet and its appurtenances effectuate the rotative movement of the piston and in turn the chuck and the cutting tool in accordance with the common practice in machines of this type.

The head block 24 is formed with a throttle valve 44 to control the supply of compressed fluid admitted to the machine. Adjacent the head block 24 is a feeding mechanism 45, but since this portion of the machine forms no part of the present invention it will not be described in detail. A port 46 leads from the throttle valve 44 to the chamber housing the ratchet mechanism 25.

Ports 47 connect the ratchet chamber with an annular distributing recess 48.

Ports 49 and 50 communicate with the valve 20 and the opposite ends of the cylinder and are 5 adapted to conduct the motive fluid from the valve to the opposite faces of the piston 11 to reciprocate the same. An annular recess 51 in the valve block 21 is in constant communication with the distributing recess 48 and opens into 10 the canal 35 in the handle 14. A port 52 connects the canal 34 with the pressure chamber 33, and a port 53 connects the canal 42 with the pressure chamber 41.

The valve 18 is formed with a vertical recess 15 56 adapted, in one position of the valve, to establish communication between the canals 34 and 35, and a recess 57 adapted, in another position of the valve, to connect the canals 35 and 42. The valve is further provided with passages 58 20 and 59 adapted to open one of the canals 34 and 42 to atmosphere when the other thereof is in communication with the canal 35.

In the practice of this invention motive fluid is admitted through the port 46 where it flows 25 through the ratchet mechanism 25 to the valve 20 by way of ports 47. The reciprocation of the piston is effected by an intermittent flow of pressure fluid into the cylinder 10 as controlled by the valve 20 by way of recess 48 and the ports 30 49 and 50. By maintaining the control valve 18 in the position illustrated in Fig. 1, the motive fluid will flow from recess 48 into recess 51, through the canal 35, port 56, canal 34 and port 52 into the pressure chamber 33, maintaining the pin 29 in engagement with the ratchet ring 26, and thus securing the ring to its casing and effecting a normal self rotation of the piston and also of the chuck 13. The pin 37 is maintained out of engagement with the recesses 36 35 in the chuck 13 by the tension of the spring 43, the chamber 41 being open to atmosphere through the port 53 and passage 59.

Should the rotative movement of the cutting tool become restrained while drilling rock or similar material of a variable density, the self or automatic rotation of the cutting tool can readily be rendered inoperative and the tool arranged for manual rotation by turning the control valve 18 to the position illustrated in Figure 2. The motive fluid will then flow from recess 51, through 45 the canals 35 and 42 by way of the recess 57, and through the port 54 into the pressure chamber 41. As the compressed fluid overcomes the effort of the spring 43, the pin 37 will be urged into 50 one of the recesses 36, thus interlocking the chuck 13 with the cylinder casing and preventing any independent rotation of the cutting tool. Simultaneously the pressure fluid remaining in the 55 pressure chamber 33 will be exhausted by way of port 52, canal 34, and passage 58 to atmosphere. The pin 29 will be withdrawn from the recess 60 27 by the pressure exerted against the inner end of the pin by the motive fluid flowing through the ratchet mechanism and through the aperture 27, thus permitting the ring to rotate relative to the 65 drill casing. The apertures 27 permit the fluid within the ratchet mechanism 25 to impinge the outer end of the pin or plunger 29 and upon alternate application of fluid under pressure to the outer end of the pin and to the headed portion 30 thereof effect the reciprocative movement of the pin or plunger 29. The bore 39 is vented to atmosphere to permit the reciprocative movement of the headed portion 38 of the pin or plunger 37.

A manual oscillation applied to the handle 14 will obviously be transmitted to the cutting tool, the chuck 13 being interlocked with the cylinder casing by the pin 37. The automatic rotation can be at any time reinstated by turning the control valve 18 to the position illustrated in Figure 1.

Although the foregoing description is necessarily of a detailed character in order to completely set forth the invention, it is to be understood that the specific terminology is not intended to be restrictive or confining, and it is to be further understood that various rearrangements of parts and modifications of structural details may be resorted to without departing from the scope or spirit of the invention as herein claimed.

We claim:

1. In a fluid-actuated machine of the class specified, a cylinder, a piston reciprocable therein, an automatic rotation mechanism coordinated with said piston and comprising a ratchet ring, a rifle stem engageable with said piston, pawls operatively connecting the ring and the stem, a chuck adapted to receive a cutting tool, a housing having a chamber therein, a fluid operated plunger in said chamber for locking said chuck to said cylinder, a spring within said chamber for retracting the plunger from the chuck when the fluid pressure is released, a second housing having a chamber therein, a second fluid operated plunger within the last named chamber for securing said ratchet ring against rotation, a fluid passageway intermediate said cylinder and said last named chamber and forwardly of said second named plunger, a control valve, fluid passageways communicating therewith and with both of said chambers for said plungers, a fluid passageway intermediate said valve and said cylinder, a handle for said control valve, the body thereof defining canals for admitting fluid under pressure to the first named plunger and to the second named plunger, exhaust ports in said control valve, said canals and said exhaust ports being arranged in a manner such that when pressure fluid is admitted to one of the plungers to effect a locking action the pressure fluid is vented through the valve from the other plunger to thereby simultaneously effect an unlocking action of the latter.

2. In a fluid-actuated machine of the class specified, a cylinder, a piston reciprocable therein, an automatic rotation mechanism coordinated with said piston and comprising a ratchet ring, a rifle stem engageable with said piston, pawls operatively connecting the ring and the stem, a chuck adapted to receive a cutting tool, a housing having a chamber therein, a fluid operated plunger in said chamber for locking said chuck to said cylinder, a spring within said chamber for retracting the plunger from the chuck when the fluid pressure is released, a second housing having a chamber therein, a second fluid operated plunger within the last named chamber for securing said ratchet ring against rotation, a fluid passageway intermediate said cylinder and said last named chamber and forwardly of said second named plunger, a control valve, fluid passageways communicating therewith and with both of said chambers for said plungers, a fluid passageway intermediate said valve and said cylinder, a handle for said control valve, the body thereof defining a canal intercommunicating with said fluid passage between the valve and the cylinder and the valve and the first named plunger chamber, and a canal intercommunicating with said fluid 75

passage between the valve and the cylinder and the valve and the second named plunger chamber, exhaust ports in said valve, said exhaust ports and said canals being arranged in the valve body in a manner such as to effect retraction of one of the plungers and simultaneously effect a locking engagement of the other of said plungers.

3. In a fluid-actuated machine of the class specified, a cylinder, a piston reciprocable therein, an automatic rotation mechanism coordinated with said piston and comprising a ratchet ring, a rifle stem engageable with said piston, pawls operatively connecting the ring and the stem, a chuck adapted to receive a cutting tool, a housing having a chamber therein, a fluid operated plunger in said chamber for locking said chuck to said cylinder, a spring within said chamber for retracting the plunger from the chuck when the fluid pressure is released, a second housing having a chamber therein, a second fluid operated plunger within the last named chamber for securing said ratchet ring against rotation, a fluid passageway intermediate said cylinder and said last named chamber and forwardly of said second named plunger, a control valve, fluid passageways communicating therewith and with both of said chambers for said plungers, a fluid passageway intermediate said valve and said cylinder, a handle for said control valve, the body thereof defining canals communicating with the passageway between the cylinder and valve and with the first named plunger chamber and second named plunger chamber respectively, the body of the handle further defining an opening aligned for communication with said passageways to said chambers and with openings to atmosphere in the control valve housing whereby, upon manipulation of said handle, one of said plungers will be actuated in locking engagement and the other of said plungers simultaneously retracted.

4. In a fluid-actuated machine of the class specified, a cylinder, a piston reciprocable therein, an automatic rotation mechanism coordinated with said piston and comprising a ratchet ring, a rifle stem engageable with said piston, pawls operatively connecting the ring and the stem, a chuck adapted to receive a cutting tool, a housing having a chamber therein, a fluid operated

plunger in said chamber for locking said chuck to said cylinder, a spring within said chamber for retracting the plunger from the chuck when the fluid pressure is released, a second housing having a chamber therein, a second fluid operated plunger within the last named chamber for securing said ratchet ring against rotation, the housing for said second named plunger chamber having a port disposed forwardly of said plunger and communicating with said cylinder, 10 a valve and separate passageways providing fluid communication of the valve with both of said plunger chambers for controlling the admission of fluid under pressure thereto, and an exhaust passage in said valve disposed to permit the es- 15 capement of pressure fluid to atmosphere, said exhaust passage and said passageways having such relative arrangement that the valve may be manipulated to effect simultaneous reverse actuation of said plungers into locking and unlock- 20 ing positions.

5. In a pneumatic tool, a cylinder, a piston reciprocable therein, a chuck associated with said cylinder, mechanism for rotating said chuck, fluid operated means for locking said chuck rotating mechanism, fluid operated means for locking said chuck with said cylinder, and a valvular mechanism common to said chuck rotating lock and said chuck cylinder lock for simultaneously reversely actuating said plungers into locking and unlocking positions. 25 30

6. In a fluid actuated machine, a cylinder, a piston reciprocating therein, a rotation mechanism comprising a ratchet ring, a rifled stem engageable with said piston, pawls operatively connecting the ring and the stem, a chuck associated with said cylinder formed to receive the cutting tool, fluid operated means to lock said rotation mechanism and other fluid operated means for locking the chuck against movement relative to said cylinder, and fluid operated valve mechanism common to said rotation locking means and the means for locking the chuck relative to the cylinder for simultaneously reversely actuating said plungers into locking and unlocking engagement for one valve position. 40 45 50 55 60 65 70 75 80 85 90 95 100
